The ornamental design for an oral irrigator handle, as shown and described.

DESCRIPTION

FIG. 1 is a front isometric view of an oral irrigator handle showing our new design.

FIG. 2 is a rear isometric view of the oral irrigator handle of FIG. 1.

FIG. 3 is a front elevation view of the oral irrigator handle of FIG. 1.

FIG. 4 is a rear elevation view of the oral irrigator handle of FIG. 1.

FIG. 5 is a left side elevation view of the oral irrigator handle of FIG. 1.

FIG. 6 is a right side elevation view of the oral irrigator handle of FIG. 1.

FIG. 7 is a top plan view of the oral irrigator handle of FIG. 1; and,

FIG. 8 is a bottom plan view of the oral irrigator handle FIG. 1.

The broken line showing of the oral irrigator tip illustrates environment and forms no part of the claimed design. All other broken lines in the drawings illustrate portions of the oral irrigator handle that form no part of the claimed design.
